AUGUST KAZENMAIER AND EUGEN BAUER, OF STUTTGART, GERMANY, ASSIGNEES TO
THE FIRM OF ROBERT BOSCH, OF STUTTGART, GERMANY.

STARTING APPARATUS FOR INTERNAL-COMBUSTION ENGINES.

1,275,941.

Specification of Letters Patent. Patented Aug. 13, 1918.

Original application filed March 6, 1914, Serial No. 822,877. Divided and this application filed February 4, 1916. Serial No. 76,205.

To all whom it may concern:

Be it known that we, AUGUST KAZENMAIER and EUGEN BAUER, both subjects of the Emperor of Germany, and residents of Stuttgart, Germany, have invented certain new and useful Improvements in Starting Apparatus for Internal-Combustion Engines; and we do hereby declare the following to be a full, clear, and exact description of the invention, such as will enable others skilled in the art to which it appertains to make and use the same.

This application is a division of our co-pending application, Serial No. 822,877, filed March 6, 1914 for starting apparatus for internal combustion engines. The main application relates to the combination with means for preliminarily rotating a rotatable element, of means for preventing the engagement between the rotating element and the engine until the kinetic energy stored up is normally sufficient to bring the engine from rest to a speed at which the normal cycle of operation is reliably established, and it covers specifically in such a combination an electric system wherein, upon closing the switch between the source of current supply and the motor, the rotatable element is first brought to a sufficiently high speed, whereupon the motor current is interrupted or reduced to a low value, and connected with the engine, and wherein the rotatable element is subsequently disconnected from the engine automatically. The present divisional application is intended to cover a starting system of this kind, wherein a manually-operated starting lever is provided to initiate the operation of the starting system, the rotating element being connected with the engine either automatically or by a further movement of the starting lever. In both cases, the rotating element is prevented from becoming connected with the engine until the current supply to the motor has been interrupted or reduced to a small value. In the first case, the starting lever is immediately released, the connection between the rotating element and the engine, as well as the disconnection, being effected automatically, whereas in the second case, the connection and disconnection must be effected by hand at appropriate periods, although the proper sequence of operation is made compulsory,

In the accompanying drawings, diagrammatically illustrating the present invention,

Figure 1 shows an embodiment wherein the starting motor and the clutch between the rotatable element and the engine are compelled by a manually-operated starting lever to be connected and disconnected in the proper sequence by further operation of the lever; and

Fig. 2 shows an arrangement similar to that of Fig. 1, excepting that the subsequent operations occur automatically.

In both modifications, the source of electric current comprising the battery *a* is connected to the exciting winding *b* of the automatic switch or circuit breaker *c*, from which the current passes through the contacts *m*, *n*, to the series electric motor *d*. The spring *k* normally holds the armature *l* depressed, and thereby holds the movable contact *m* away from the stationary contact *n*.

The clutch member *v* is fastened on the motor shaft *x* in position to be engaged in driving connection by the co-operative clutch member *5*, which is mounted for longitudinal shifting movement. The clutch member *5* is fast with a pinion that drives the gears *6* on a counter shaft which, in turn, is adapted to drive the crank shaft *w* of the internal combustion engine through the intermediary of an overrunning clutch *11*.

In the modification shown in Fig. 1, the first part of the movement of the manually-operated hand lever *13* closes the circuit from the source of current supply to the starting motor, but is locked in position from further movement until the starting current decreases to a value at which the circuit is interrupted or reduced to a low value if desired, whereupon the lever may then be moved to close the clutch between the rotating element and the internal combustion engine to start the engine into operation. The starting lever *13* carries a rail *14* and can be moved between the positions *O* and *I* shown in broken lines. The rail *14* is connected by the links *16* and *17* to the rod *18* which carries an arm *19* for shifting the clutch member *5* into and out of engagement with the co-operative clutch member *v*. The clutch member *v* is fastened on the shaft of the starting motor *d* while the clutch member *5* is shiftable along its shaft by reason of

a feather and groove connection therewith. The rail 14 carries a spring lever 20 having a knob 21 on its end, and the rail also carries a lug 22. A guide 23 separate from the rail 14, is provided with inclined outer surfaces. A bent lever 24 is pivoted to the piece 25 and is pressed by the spring 26 against an abutment on the piece 25. The lever 24 has a projection lying within the path of movement of the armature *l*, and also has its end in the line of movement of the stop 22 when the lever 24 is held in raised position by the spring 26.

The operation of the arrangement shown in Fig. 1 is as follows: In order to start the engine from rest, the starting lever 13 is moved from its O position to shift the rail 14 toward the right. During this movement the knob 21 slides along the surface 27 of guide 23 and through the intermediary of the projection 12 raises the armature *l* until the contact *m* is brought into engagement with the contact *n*, whereupon the starting current flows from the battery *a* through the winding *b* of the electromagnet *c* and thence through the series motor *d* back to the battery. At the same time the lever 24 is raised by its spring 26 so that its end projection prevents further longitudinal movement of the projection 22 beyond it. The motor *d* speeds up until a speed, say about six hundred revolutions per minute, at which the required energy is stored in the rotating parts, comprising the rotating element *v* and associated parts, is reached. The arrangement is such that when this predetermined speed is reached, the starting current has become so small in value that the attraction of the armature *l* is overcome by the stress of the spring *k*. The armature *l* is thereupon forced down, and in its movement pushes the end of the lever 24 against the stress of spring 26 out of the path of the lug 22. Up to this time, the starting lever 13 was prevented from further movement so that the clutch *v*, *5* was compelled to be open, but after this time the starting lever 13 may be moved to its position I to close the clutch *v*, *5* and thereby apply the energy stored in the rotating parts. During this latter portion of the movement of rail 14, the knob 21 is raised by the inclined surface 28 to such a point that it thereafter snaps under the guide 23, so that when the rail 14 is being moved back to its O position the knob 21 does not lift the armature *l*. When the rail 14 has reached its O position, the knob 21 snaps into its normal position so as to slide along the surface 27 of the guide 23 when the rail is again moved to the right. The armature *l* holds the lever 24 depressed until the armature is again raised by the knob 21. When the engine is running under its own power, the starting lever 13 is moved back to its position O to

thereby disconnect the motor from the engine.

In the embodiment shown in Fig. 2, the clutch between the rotatable element and the engine is closed automatically after the starting current to the motor is interrupted without any subsequent movement of the starting lever, and furthermore the clutch is opened automatically to disconnect the starting apparatus from the engine and the lever is automatically returned to its starting position, when the starting lever is released after the engine has come up to speed. The clutch member *v* is fastened on the shaft *x* of the armature of the series motor *d*, while the co-operative clutch member *5* is slidable thereon in constant driving connection therewith. The abutment 22 is carried on a rod 29 slidable longitudinally of the rail 14. The outer end of the rod 29 is provided with an end projection 31 in line with the shaft of the clutch member *5*, and the spring 30, when compressed, tends to move the rod 29 to the right relatively to the rail 14. The tension spring 32 tends to return the rail 14 and the starting lever 13 to their O position when the starting lever 13 is released, and the compression spring 33 tends to separate the clutch members *v* and *5* from driving engagement.

The operation of the arrangement shown in Fig. 2 is as follows: To start the engine from rest, the starting lever is moved from its O position to the position indicated by I, the rail 14 being thereby moved to the right against the stress of spring 32. During this movement of the rail 14, the armature *l* is raised until the contacts *m*, *n* engage each other and thereby close the circuit from the battery through the winding *b* and the starting motor *d*. The rod 29 is moved to the right by the compression spring 30 until the abutment 22 carried by the rod 29 is prevented from further movement by the end of the spring pressed pivoted lever 24. As soon as the starting current has fallen sufficiently, the spring *k* overcomes the attraction on the armature *l* and thereby depresses the armature and pushes the end of the lever 24 out of the path of further movement of the stop 22, whereupon the compression spring 30 forces the end 31 of the rod against the shaft of the clutch member *5*. The clutch is closed in this way against the stress of the compression spring 33, and the energy of rotation stored in the rotating element is applied through the gears 6 and the overrunning clutch 11 to the crank shaft *w* to start the engine from rest. When the engine reaches a predetermined speed under its own power, the starting lever 13 is released, and the clutch members *v* and *5* are disconnected by the stressed spring 33, while the rail 14, with the rod 29 and also the starting lever 13, are brought

to their O position by the stressed spring 32. The remaining features of operation of this modification will be apparent from the foregoing description of the arrangement 5 shown in Fig. 1.

What we claim is:

1. In apparatus for starting internal combustion engines from rest, a source of electric current, a rotatable element designed to be connected with and disconnected from the engine, an electric starting motor for driving the rotatable element, an electromagnetic switch having contacts in the circuit of the motor and having an energizing winding calibrated to open said contacts when the current to the motor reaches a predetermined low value corresponding to a motor speed appropriate for starting the engine, mechanism, including a manually-operated lever, for connecting the rotatable element to the engine, and means preventing said mechanism from connecting the rotatable element to the engine until said contacts are opened.
2. In apparatus for starting internal combustion engines from rest, a source of electric current, a rotatable element designed to be connected with and disconnected from the engine, an electric starting motor for driving the rotatable element, an electromagnetic switch having contacts in the circuit of the motor and having an energizing winding calibrated to open said contacts when the current to the motor reaches a predetermined low value corresponding to a motor speed appropriate for starting the engine, mechanism, including a manually-operated lever for connecting the rotatable element to the engine, means preventing said mechanism from connecting the rotatable element to the engine until said contacts are opened, and automatic means for disconnecting the rotatable element from the engine after the engine starts into operation under its own power.

3. In apparatus for starting internal combustion engines from rest, a source of electric current, a rotatable element, an electric starting motor for driving the rotatable element, a clutch for mechanically connecting the rotatable element with the engine, an automatic circuit breaker having contacts in the circuit of the motor and having an energizing winding calibrated to open said contacts when the current to the motor reaches a predetermined low value corresponding to a motor speed appropriate for starting the engine, a starting lever having means to close said contacts, a member slidably mounted on the starting lever so as to be movable relatively thereto and being adapted to close the clutch, and locking mechanism arranged, when the circuit breaker is closed, to hold the slidable member in such position that the clutch is open, and arranged, when the circuit breaker is open, to permit the movement of the slidable member to close the clutch.

4. In apparatus for starting internal combustion engines from rest, a source of electric current, a rotatable element designed to be connected with and disconnected from the engine, an electric starting motor for driving the rotatable element, an electromagnetic switch having contacts in the circuit of the motor and having an energizing winding calibrated to open said contacts when the current to the motor reaches a predetermined low value corresponding to a motor speed appropriate for starting the engine, a reciprocating starting lever having means, when moved in one direction, to close said contacts, and a guide preventing said means from closing said contacts when the starting lever is moved in the opposite direction.

In testimony whereof, we affix our signatures.

AUGUST KAZENMAIER.
EUGEN BAUER.
